UNITED STATES PATENT OFFICE.

WILLIAM B. LONGEST, OF LOUISVILLE, KENTUCKY.

PRIMING DEVICE FOR INTERNAL-COMBUSTION ENGINES.

1,300,749.

Specification of Letters Patent. Patented Apr. 15, 1919.

Application filed May 21, 1918. Serial No. 235,835.

To all whom it may concern:

Be it known that I, WILLIAM B. LONGEST, a citizen of the United States, and resident of Louisville, in the county of Jefferson and 5 State of Kentucky, have invented certain new and useful Improvements in Priming Devices for Internal-Combustion Engines; and I do hereby declare the following to be 10 a full, clear, and exact description of the invention, such as will enable others skilled in the art to which it appertains to make and use the same.

This invention relates to improvements 15 in priming devices for internal combustion engines,—one object of the invention being to improve and simplify priming devices of that type which are adaptable for connection with the manifold and provide means for atomizing fuel into the manifold 20 when the crank or self starter is operated, to facilitate the prompt starting of the engine.

A further object is to provide a priming 25 structure of the type specified, in which the atomizer element can be readily adjusted.

With these and other objects in view, the 30 invention consists in certain novel features of construction and combinations of parts as hereinafter set forth and pointed out in the claims.

In the accompanying drawings; Figure 1 is a view partly in elevation and partly in section showing one embodiment of my invention, Fig. 2 is a plan view, and Fig. 3 35 is a view showing a modification.

1 represents the intake manifold of an internal combustion engine; 2 the intake pipe provided with a suitable throttle valve 3, and 4 is a diagrammatical representation 40 of a carbureter.

My improved priming device is supported by the intake pipe and comprises a reservoir 5 to receive a supply of gasolene, a threaded nipple 6 being connected with the 45 reservoir and screwed through the wall of the intake pipe.

The wall of the reservoir is made with an 50 interior enlargement 7 having an opening 8 extending through the wall of the reservoir for the passage of the shank portion of the nipple 6. A portion 9 of this shank is made slightly tapering to fit tightly in the outer tapering portion of the opening 8, and near said tapering portion 9, the 55 shank of the nipple is made with a circumferential groove 10 which communicates

with a duct 11 extending outwardly through the nipple; said groove being also adapted to communicate with the upper end of a duct 12 which extends downwardly through the 60 enlargement 7 and is open at its lower end near the bottom of the reservoir. The nipple 6 is also made with a duct 13 (somewhat larger than the duct 11) which extends from end to end of said nipple,—said duct 13 65 constituting an air duct communicating at its inner end with the interior of the reservoir.

A tube 14 communicates with the air duct 13 and projects from the inner end of the 70 nipple 6 so as to terminate within the intake pipe, preferably at or near the longitudinal center thereof. The free end of the air tube is closed, and is provided near such closed end, with transverse openings 15 and 16. A fuel tube 17 (smaller in diameter than the air tube 14) communicates with the fuel duct 11 and its free open end is bent laterally and enters the hole 16 of the air 75 tube, so as to terminate within the latter and discharge through the hole 15 in said air tube. The tubes 14 and 17 thus form an atomizer for spraying combined air and fuel from the reservoir into the intake pipe to facilitate the starting of the engine. 80

The nipple 6 is held properly to its seat in the wall of the reservoir by means of a spring 18 which encircles the shank portion of said nipple and bears against the internal 85 enlargement 7 of the reservoir and against a pin 19 passing transversely through the end portion of said shank. By thus connecting the nipple, carrying the atomizer, with the reservoir, it can be turned to adjust the atomizer and cause the latter to discharge in a direction longitudinally of the intake tube, regardless of the position of the latter,—whether the same be vertical, inclined or horizontal. To facilitate the 90 turning and adjusting of the nipple, the same may be made with an angular portion 95 20 to receive a wrench.

The reservoir 5 may be supplied with 100 gasolene through a pipe 21 connected with a suitable source of supply conveniently located and any suitable manually operable valve devices (not shown) may be employed for controlling the flow of gasolene to the reservoir.

A float 22 is located within the reservoir 110 and provided with a stem 23 which passes through an air hole 24 in the cover 25 of said

reservoir,—said stem having a knob or enlargement at its upper end which constitutes a valve 26 for normally closing said air hole. When the reservoir is supplied with 5 gasolene, the float will rise and lift the valve 26 to open the air inlet to admit air for the atomizer, and when the engine shall have been primed, the reservoir will have been emptied and the valve 26 will be closed by 10 the descent of the float.

In the form of the invention shown in Fig. 3, the reservoir is provided with a swinging cover 27 having a thumb piece 28 to facilitate the opening of the reservoir to 15 permit the filling of the same with gasolene, and said cover is retained normally in position by the engagement of a tip 29 thereon with a notch 30 in the upper end of the reservoir wall. During the priming operation, the cover 26 will be moved aside to admit air.

When the engine is being started (by cranking in the usual way, or by means of a self-starter, with the throttle closed or 25 partly closed), the suction created by the operation of the pistons of the engine will cause air to enter the larger tube 13—14 and to be ejected from the nozzle at 15 into the intake pipe, thus causing gasolene to be 30 drawn through the smaller tube 17 and discharged or sprayed into the intake pipe and manifold, from whence it is drawn into the engine.

Other slight changes might be made in the 35 details of construction of my invention without departing from the spirit thereof or limiting its scope and hence I do not wish to restrict myself to the precise details herein set forth.

40 Having fully described my invention what I claim as new and desire to secure by Letters-Patent, is:—

1. In a priming device, the combination with a tank, a nipple to communicate therewith and adapted to enter the intake of an engine, and an atomizer at the end of the 45 nipple which enters the intake, and means adjustably connecting the nipple and tank whereby said nipple may be turned to cause 50 the atomizer to discharge longitudinally of the intake whether the latter be disposed vertically, horizontally or in an inclined position.

2. In a priming device, the combination 55 with a reservoir, of a nipple adapted to enter the intake of an engine, said nipple having a part passing through and seated in the wall of the reservoir and adapted to be turned, a spring holding said nipple to its 60 seat, said nipple having a groove, a duct in the nipple communicating with said groove, a duct in the reservoir communicating with

said groove and with the lower portion of the reservoir, an air duct passing through said nipple, and an atomizer comprising two 65 members, carried by the nipple and having its members communicating respectively, with the ducts in the nipple.

3. In a priming device, the combination with a reservoir, of a nipple projecting therefrom and adapted for connection with the intake of an engine, said nipple having air and fuel ducts, and a duct in the reservoir communicating with the fuel duct in the nipple and with the lower portion of the 70 reservoir, and an atomizer comprising an air tube communicating with the air tube in the nipple and closed at its free end, said air tube having lateral holes, and a fuel tube communicating with the fuel duct in the 75 nipple and entering one of the lateral holes of the air tube.

4. In a priming device, the combination with a reservoir having an internal enlargement in the wall thereof provided with a 80 fuel duct and a lateral opening, of a nipple seated in said lateral opening of the reservoir and having a fuel duct communicating with the fuel duct in said enlargement, said 85 nipple having an air duct extending therethrough, and an atomizer comprising two members, carried by said nipple and having its respective members in communication with the air and fuel ducts in said nipple.

5. In a priming device, the combination 90 with a reservoir, means for supplying fuel thereto, a float in said reservoir, a cover for the reservoir having an air hole, and a valve for said air hole, carried by the float, of a 95 nipple adjustably connected with the reservoir and adapted for connection with the intake of an engine, an atomizer carried by said adjustable nipple, air and fuel ducts in the nipple communicating with said atomizer, and a duct in the reservoir connecting 100 the lower portion of the latter with the fuel duct in the nipple.

6. In a priming device, the combination with a reservoir having an air inlet, of a 105 nipple connected with said reservoir and adapted for connection with the intake of an engine, an atomizer carried by said nipple and communicating with the interior of the reservoir, a float in said reservoir and a valve connected with said float for opening 110 and closing said air inlet.

In testimony whereof, I have signed this specification in the presence of two subscribing witnesses.

WILLIAM B. LONGEST.
